UNITED STATES PATENT OFFICE.

JAMES M. DE WITT, OF RUTHERFORD, NEW JERSEY.

CAR-CHECK.

SPECIFICATION forming part of Letters Patent No. 468,061, dated February 2, 1892.

Application filed September 2, 1891. Serial No. 404,559. (No model.)

To all whom it may concern:

Be it known that I, JAMES M. DE WITT, of Rutherford, county of Bergen, State of New Jersey, have invented new and useful Car-
5 Checks, the same being an improvement upon that described in Letters Patent of the United States of America granted me June 17, 1884, No. 300,448, and June 11, 1889, No. 404,901, of which the following is a specification.

10 My invention relates to preventing the accidental movement of cars on side tracks and arresting the backward movement of detached cars while ascending a grade.

Reference is to be had to the accompanying 15 drawings, forming a part of this specification, in which similar letters of reference indicate corresponding parts in all the figures.

Figure 1 is a side view of the check-block. Fig. 2 is an end view of same. Fig. 3 is a 20 large view of the pawl. Fig. 4 is another view of the pawl. Fig. 5 is a view of my improvement patented June 17, 1889, No. 404,901. Fig. 6 is a view of the pawl with my improvement attached. Fig. 7 is a view of the check- 25 block patented June 17, 1884, No. 300,448.

The check-block A has a lug B on one side to prevent hook ends of staple-like rod C from rising up even with lower edge of check-block A.

In Fig. 2 is shown an end view of the check-block provided with a lug B on both sides of check-block A. The pawl D has slot and hinged part, as shown in Fig. 3. The pawl D has an attachment E for holding one end of spring F. The spiral spring F is attached 35 at one end to pawl D at E and at the other end to lower edge of guard G. This spring F is intended to draw the pawl D back to its proper position with reference to ratchet-wheels H and J after the car has moved forward.

Having thus described my invention, what I claim as new, and desire to secure by Letters Patent, is—

1. The check-block provided with staple-like rods and also with suitable projections above said rods to prevent them from rising up even with the lower edge of the block, substantially as described.

2. The combination of the pawl, ratchet-wheels, and the spring F, substantially as described.

JAS. M. DE WITT.
